Primary Examiner — Paula Greene(74) *Attorney, Agent, or Firm* — Chris J. Katopis(57) **CLAIM**

The ornamental design for an earbud, as shown and described.

DESCRIPTION

FIG. 1 is a front perspective view of an earbud, showing the new design;

FIG. 2 is a front view thereof;

FIG. 3 is a back view thereof;

FIG. 4 is a side view thereof;

FIG. 5 is the opposite side view thereof;

FIG. 6 is a top view thereof; and,

FIG. 7 is a bottom view thereof.

In all figures, the broken lines represent environmental subject matter that forms no part of the claimed design.

1 Claim, 7 Drawing Sheets(56)
